UNITED STATES PATENT OFFICE.

ERNST ZINDEL, OF ERLENBACH, SWITZERLAND, ASSIGNOR TO THE FIRM SCHARER-NUSSBAUMER & CO., OF ERLENBACH, SWITZERLAND.

WINDING MACHINE.

Application filed August 25, 1921. Serial No. 495,211.

To all whom it may concern:

Be it known that I, ERNST ZINDEL, a citizen of the Republic of Switzerland, residing at Erlenbach, Switzerland, have invented 5 certain new and useful Improvements in Winding Machines (for which I have filed applications in Switzerland, May 18th, 1920, Patent No. 88358; in France, June 15, 1920, Patent No. 517190; in Italy, June 15th, 1920, 10 application No. 292/1923; in Switzerland, October 25th, 1920, application No. 9032; in France, April 29th, 1921, application No. 14424; in Germany, May 6th, 1921, application Sch. 61603; and in Belgium, May 15th, 1921, application No. 236869); and I do hereby declare the following to be a full, clear, and exact description of the invention, such as will enable others skilled in the art to which it appertains to make and 20 use the same, reference being had to the accompanying drawings, and to letters or figures of reference marked thereon, which form a part of this specification.

This invention relates to improvements 25 in winding machines and particularly to a locking device of the clamping type for the member carrying the thread guides and the feeler which member is moved intermittently on the cops being wound.

It is already known in winding machines to provide a locking device for the above mentioned member which device takes part together with the carrier member in the intermittent movements of the latter in one 35 direction and which locks that member in its momentary position and prevents it from carrying out an undesired movement in the opposite direction. According to my invention the locking device is provided with a clamping sleeve mounted on the guide rod of said member and which locking device is adapted to lock the carrier member by means of an abutment member cooperat- 40 ing with a tapering surface.

A locking device of this type presents 45 the advantage as compared with the known devices of a greater simplicity and of being influenced to a much smaller degree by dirt and oil. The abutment member may be formed by an adjustable pin enabling an adjustment of the tension of a spring co-acting with the clamping sleeve and thereby varying the clamping action of the sleeve. In a preferred construction the abutment member may consist of a roller whereby the

sensitiveness of the clamping device is materially increased.

Three constructional examples of the invention are illustrated on the accompanying drawings, in which—

Fig. 1 shows a vertical longitudinal section taken on line I—I in Fig. 2 of the first form of the locking device.

Fig. 2 is a cross-section on line II—II of Fig. 1.

Fig. 3 is a diagrammatic view of a winding machine fitted with the locking device according to the invention.

Fig. 4 shows a vertical longitudinal section on line IV—IV of Fig. 5 of a second 70 constructional example of the locking device.

Fig. 5 is a cross-section on line V—V of Fig. 4.

Fig. 6 illustrates a modification of a detail of the second constructional example.

Referring to the first constructional example illustrated in Figs. 1-3, 1 denotes the guide rod for the carrier member 2, which is mounted on the rod 1 with little radial clearance. The guide rod 1 made of a circular bar is along its guide part proper of a triangular cross-section (Fig. 2). Into the enlarged part at one end of the bore of the sleeve 3 fixed to the member 2 the clamping sleeve 4 projects, the latter surrounding the rod 1 with little clearance. The sleeve 4 is provided at its outer surface with a tapering face 4', in the exemplification shown the tapering facing 4' extends over its whole circumference and forming thus a conical surface, which is pressed by the action of a compression spring 5 against the rounded head of a set screw 6. The latter acts as the abutment member and is adapted to be adjusted in the sleeve 3. The sleeve 4 is clamped between the parts 6 and 1 whereby the carrier member 2 is clamped to the guide rod 1 in the position shown. 7 denotes the feeler of a known kind turnably mounted on a ball bearing 13 in the carrier member 2, the feeler 7 being provided with a conical bore 14 arranged in the longitudinal axis of the cop spindle 9. The cop spindle 9 which is parallel to the guide rod 1 performs during the operation of the winding machine a reciprocating and simultaneously a turning motion, the gear for imparting such motions is arranged inside the casing 12 and may be of a similar

100
105
110

construction to that disclosed in my United States Patent No. 1000695 dated May 18th 1911, or in my Swiss Letters Patent No. 72613. 10 denotes the thread guide provided on the carrier member 2 and 11 denotes a cop.

Upon its movement in the axial direction the cop 11 enters into the conical bore of the feeler 7, turns the latter and effects a 10 pressure on the carrier member 2. Thereby the spring 5 is compressed, the clamping of the sleeve 4 is counteracted and a displacement of the carrier member 2 is thereupon effected. As soon as said pressure upon the 15 carrier member 2 ceases the spring 5 expands and presses the sleeve 4 with its conical part against the set screw 6 so that the sleeve 4 is again clamped between the rod 1 and the screw 6 and the carrier member 2 20 is locked in its new position. By adjusting the set screw 6 the tension of the spring 5 and thereby the clamping action of the sleeve 4 can be regulated at will. The prismatic shape of the guide rod 1 enhances the 25 clamping action of the sleeve 4.

Referring now to the second constructional example illustrated in Figs. 4 and 5, 21 denotes again the guide rod, which is of a circular cross-section throughout its 30 length. The carrier member 22, the sleeve 23 rigidly connected to the latter and surrounding the guide rod 21 with little clearance, the sleeve 24 with its conical outside 35 surface 24', the spring 25 and the feeler 27 are of substantially the same design as in the above described constructional example and illustrated in Figs. 1-3. The essential 40 difference between these two constructional examples consists in the design of the abutment member which, in this case, is a roller 26 mounted upon a conical pin 26' which is 45 fixed to the sleeve 23. The manner of operation of this locking device is exactly the same as that of the previous example as described above.

The provision of the roller 26 as abutment member for the tapering surface facilitates to suspend temporarily the engagement between said surface and the abutment member and thereby facilitates the operation of 50

the locking device. The locking device can easily be dismantled into its various parts.

The tapering or the conical surface 23' may also be provided on the sleeve 23 and the roller 26 may be mounted on the sleeve 24 as shown in Fig. 6. In this case the sleeve 23 is made in halves.

I claim:

1. In a locking device for cop winders, a carrier, a sleeve member thereon, a guide rod loosely passing through said member, a second member loose on said rod, one of said members having a conical surface, an element on the other member cooperating with said conical surface, and a spring between the two members, whereby upon movement of the carrier and sleeve member the spring will be compressed to release said second member from its one-sided clamping engagement with said rod to permit said carrier to progress along said rod.

2. In a locking device for cop winders, a supporting rod, two members on said rod one within the other, one of said members having a conical surface facing the other member and said other member having thereon a single element co-operating with said conical surface to produce a one-sided clamping action of the interior member on said rod, and a spring between the elements.

3. In a locking device for cop winders, a supporting rod, two members on said rod one within the other, one of said members having a conical surface, a roller on the other member cooperating with said surface, and a coil spring on said rod between the members, whereby the interior member has a one-sided clamping action on said rod.

4. In a locking device for cop winders, a supporting rod triangular in section, two members loose on said rod one within the other, a coil spring on said rod between the members, one of said members having a conical surface, and means on the other member cooperating with said surface to cause the interior member to clamp said rod.

In testimony whereof I have signed my name to this specification.

ERNST ZINDEL.
